UNITED STATES PATENT OFFICE.

GEORGE L. BUMGARDNER, OF GRIDLEY, KANSAS, ASSIGNOR OF ONE-HALF TO HARRY A. PATRIGE, OF GRIDLEY, KANSAS.

VEHICLE-COUPING.

1,269,377.

Specification of Letters Patent. Patented June 11, 1918.

Application filed July 13, 1917, Serial No. 180,397. Renewed April 12, 1918. Serial No. 228,279.

To all whom it may concern:

Be it known that I, GEORGE L. BUMGARDNER, a citizen of the United States, residing at Gridley, in the county of Coffey, 5 State of Kansas, have invented certain new and useful Improvements in Vehicle-Couplings; and I do hereby declare the following to be a full, clear, and exact description of the invention, such as will enable others 10 skilled in the art to which it appertains to make and use the same.

This invention is an improvement in vehicle couplers and has particular reference to a bolster construction.

15 An object of the invention is to dispense with the usual king bolt employed in connection with constructions of this character and which extend through the axle, sand-board, and bolster, thereby weakening said 20 parts, and, to this end, use is made of a plurality of bolster plates of improved construction certain of which are carried by the sand-board, while the others are attached to the bolster and engaged with the 25 first mentioned plates in such manner as to permit of the swinging of the bolster when the vehicle is being turned.

Another object of the invention is to provide a coupler of this character which is 30 simple in construction, easy to manufacture and effective in carrying out the purpose for which it is designed.

The inventive idea involved is capable of receiving a variety of mechanical expressions, one of which, for the purpose of illustrating the invention, is shown in the accompanying drawing, wherein:

Figure 1 is a top plan view of the coupling mechanism of a vehicle constructed in 40 accordance with the invention.

Fig. 2 is a front elevation thereof.

Fig. 3 is a longitudinal section on the line 3—3 of Fig. 1.

Fig. 4 is a transverse section on the line 45 4—4 of Fig. 1 taken longitudinally through the bolster.

Fig. 5 is a horizontal section on the line 5—5 of Fig. 2.

Fig. 6 is a detail perspective view of the 50 adjustable bolster plates.

Fig. 7 is a similar view of the coupler pole or reach member, and

Fig. 8 is a similar view of one of the 55 clamping plates employed in connection with the invention.

In the drawings, the numeral 10 indicates the front axle of a vehicle and 11 the sand-board which parts have interposed therebetween and extending forwardly and rearwardly therefrom the usual braces or hounds 60 12 which are secured thereto by the bolts 13. Centrally of the axle 10 the same has mounted on the top and bottom edges thereof clamping plates 14 each of which consists of an enlarged central portion 15 provided 65 with reduced extensions 16 at each end having longitudinal flanges 17 which receive the axle therebetween. The under side of the sand-board 11 also has a clamping plate 18, similar in construction to the plates 14, 70 secured thereto by means of the bolt 19 which extends through the axle, the plates 14 and 18 and said sand-board, said bolts being surrounded by spacing sleeves 20 interposed between the uppermost plate 14 75 and the plate 18.

The bolster construction which comprises one of the essential features of the invention preferably consists of a stationary portion including a base member 21 preferably 80 in the form of an oval plate also secured to the sand-board by means of bolts 19. The base member is provided adjacent each end with superposed end plates 23 and 24 secured to the base member by riveting or otherwise. 85 The plates 23 and 24 are preferably cut away or curved as indicated at 25 and 26 respectively and the curved edge of the plate 24 extends inwardly toward the center of the base member 21 a greater distance than the 90 curved portion of the plate 23 whereby to provide guide channels 27 adjacent each end of the base member for a purpose which will presently appear. At oppositely disposed points along the longitudinal edges of said 95 base member 21 and between said end plates the base member has secured thereto the guide lugs 28 by means of bolts 29 which extend downwardly through the base member and through the enlarged or central portions 100 15 of the clamping plates 14 and 18 and surrounding the bolts 29 in the space between said base member and the clamping plates are the spacing sleeves 30.

The bolster 31 is mounted above the sand 105 board 11 for swinging movement in a horizontal plane and to this end said bolster has preferably secured to the under side thereof, by means of bolts 32, the superposed adjustable bolster plates 33 and 34, riveted to 110

gether, the uppermost plate having lugs 35 engaging on either side of the bolster. The lowermost plate 33 is considerably larger than the plate 34 but of similar construction, 5 each of said plates consisting of segmental end sections 36 and 37, respectively. The curved ends of the end sections 36 of the plate 33 project into the guide channels 27 and said curved ends are disposed concentrically to the curved edges of the plates 23. The plate 34 is disposed in substantially the same horizontal plane with the plates 24 and the curved edges 26 thereof are likewise disposed concentrically to the curved 10 ends of the segments 37 of said plate 34. The inner ends of the lugs 28 also overhang the central portion of the plate 33 and thus provide a guide therefor. In this manner the bolster 31 is mounted for horizontal 15 swinging movement and through the medium of the construction described it will be apparent that the use of the usual king bolt 20 is dispensed with.

The coupling pole or reach member 38 of 25 the vehicle is preferably provided with an attaching member 39 secured to the pole by the bolt 40 and provided in the body portion thereof with a curved slot 41 through which extends the rear bolt 29. The member 39 is also provided with an opening 42 for receiving a pivot 43 extending between the uppermost clamping plate 14 and the clamping plate 18 between which said member is disposed. The member 39 is further 30 provided with shoulders 44 adapted to contact the spacing sleeves 20 surrounding the bolts 19 whereby to limit the swinging 35 movement of the pole 38.

What is claimed is:

40. 1. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, and a bolster secured to the other plate.
45. 2. In a coupler for vehicles, the combination with an axle and a sand-board; of a bolster construction including a stationary portion carried by said sand-board and having guiding channels, relatively adjustable and superposed plates associated with said

stationary portion and having segmental end sections, the end sections of one plate projecting into said guide channels, guide lugs carried by said stationary portion and forming guides for the central portion of the first named adjustable plate, lugs carried by the second named adjustable plate, and a bolster secured to said plates and disposed between the last named lugs: 60

3. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, guide lugs carried by said stationary portion and forming guides for the central portion of the first named adjustable plate, a bolster secured to said plates, a plurality of clamping plates carried by said axle and sand-board and disposed beneath said stationary base portion, and bolts arranged on each side 70 of said axle and sand-board and connecting said base portion and said clamping plates. 75

4. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, guide lugs carried by said stationary portion and forming guides for the central portion of the first named adjustable plate, a bolster secured to said plates, a plurality of clamping plates carried by said axle and sand-board and disposed beneath said stationary base portion, and bolts arranged on each side of said axle and sand-board and connecting said base portion and said clamping plates. 80

45. 5. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, guide lugs carried by said stationary portion and forming guides for the central portion of the first named adjustable plate, a bolster secured to said plates, a plurality of clamping plates carried by said axle and sand-board and disposed beneath said stationary base portion, and bolts arranged on each side of said axle and sand-board and connecting said base portion and said clamping plates. 85

50. 6. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, and a bolster secured to the other plate; 90

55. 7. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, and a bolster secured to the other plate; 95

60. 8. In a coupler for vehicles, the combination with an axle and a sand-board; of a bolster construction including a stationary portion carried by said sand-board and having guiding channels, relatively adjustable and superposed plates associated with said stationary portion and having segmental end sections, the end sections of one plate projecting into said guide channels, and a bolster secured to the other plate; 100

In testimony whereof I affix my signature 105 in the presence of two witnesses.

GEORGE L. BUMGARDNER.
